UNITED STATES PATENT OFFICE

2,572,211

RADIO DIRECTION FINDER HAVING SENSE
ANTENNA

Joseph G. Speer, Merriam, Kans., assignor of one-half to H. G. Koenig, Merriam, Kans.

Application January 12, 1948, Serial No. 1,775

12 Claims. (Cl. 343—117)

1

This invention relates to the field of radio and particularly to direction finders, the primary object being to provide a device of such character as forms the subject matter of my co-pending application, Serial No. 707,696, filed November 4, 1946, now Patent No. 2,490,660, granted December 6, 1949, this being a continuation in part thereof.

The most important object of this invention is to provide a radio direction finder that is a decided improvement over that disclosed in my said co-pending application through the addition of many novel features that greatly increase its utility.

One of such important features and improvements lies in the inclusion of a sense antenna together with a rotatable loop antenna to remove the 180 degree ambiguity in bearing indications that is inherent in the device forming the subject matter of said earlier filed application.

Another important object of this invention is the provision of a radio direction finder having a sense antenna wherein means is provided to improve operating accuracy, making possible more correct bearings on the maximum, thereby permitting continuous aural monitoring and minimizing interference from static and undesired radio signals.

Another important object of this invention is the provision of a radio direction finder including amplifier stages, having new linear amplification characteristics, in both the audio and rate of change channels, thereby maintaining the audio output and the triggering impulses approximately uniform regardless of the amplitude of the received radio signal.

A further object of this invention is to provide a radio direction finder having a voltage limiter in the rate of change channel that limits the triggering impulses to just above the value required for operation, which together with pulse time delay, renders the direction finder practically immune to bursts of static.

A still further object of this invention is the provision of a radio direction finder having a limit type of automatic volume control that is ineffective, throughout the change in signal level required for proper functioning of the direction finder, but is effective at signal level changes in excess of these requirements.

Additional features and objects will be set forth and made clear during the course of the following specification, reference being had to the accompanying drawing showing a diagrammatical view of an electric circuit forming a part

2

of a radio direction finder having a sense antenna made in accordance with my present invention, and showing schematically the loop antenna, sense antenna, motor, motor shafts, gears, radio receiver and associated parts thereof.

In the drawing a directional antenna, constituting normally an electrostatically shielded loop, is broadly designated by the numeral 10 and the numeral 12 designates a non-directional or sense antenna.

The windings of the loop 10 are connected to a pair of collector rings 14 and 16 and from the rings by means of contact brushes (not shown) to a pair of wires 18 and 20. The received signal is conducted over these wires to a radio receiver tuner amplifier 22 where it is amplified to the level required for detection. No details of these receiver elements are shown as they may be quite conventional.

The amplified radio signal is conducted through a transformer 24, which is tuned by a pair of condensers 26 and 28, to a diode 32 of a vacuum tube 30. The radio frequency signal is rectified by the diode 32 and a resultant direct current voltage appears across a resistor 34, together with a superimposed audio frequency signal if the radio signal was modulated. The radio frequency component is greatly attenuated by a condenser 36 whose value is so chosen as to cause inappreciable attenuation of the audio frequency component. These voltages are conducted through a resistor 38 to the grid 39 of vacuum tube 30. A condenser 40 contributes almost complete radio frequency attenuation and large audio frequency attenuation.

The negative direct current voltage applied to the grid 39 of the vacuum tube 30 increases its grid bias and hence reduces its plate current. The positive cathode potential as produced by the plate current flowing through a pair of resistors 52 and 54 consequently decreases as the incoming signal increases.

The audio frequency voltages appearing across the resistor 34 are conducted through a resistor 42 and a condenser 48 to the grid 49 of a vacuum tube 56. The condenser 48 blocks the direct current voltage from the grid 49. The resistor 42, a resistor 44 and a condenser 45 provide additional, almost complete attenuation of the radio frequency component and some uniform audio frequency attenuation.

The grid 49 of vacuum tube 56 is positively biased by reason of the voltage drop across the resistor 54. Therefore the cathode of tube 56

should be also positive and this is accomplished by means of a resistor 58.

The voltage drop across the resistor 54, and hence the grid bias of the vacuum tube 56, changes with signal level. If the values of the resistors 54 and 58 are suitably chosen, the change in amplification of the vacuum tube 56 will vary approximately inversely as the signal level. By this means the audible output may be held approximately constant.

The audio signal as amplified by the vacuum tube 56 is conducted from its plate over a wire 60 and through suitable coupling means (not here shown) to subsequent conventional audio amplification as required for aural indications.

The voltage at the cathode of the vacuum tube 30, which rises and falls as the signal decreases and increases respectively, is impressed upon the grid 67 of a vacuum tube 68 over a wire 66.

The cathode of the vacuum tube 68 must be more positive than the grid 67 throughout the operating range of signal levels. This positive bias may be conveniently secured from a usual storage battery 64 which in most aircraft is 12 volts or more. Noise and ripple may be removed by a choke 72 and a condenser 74.

For the vacuum tube 68, one of suitable characteristics should be chosen, and suitably loaded by a resistor 70 of proper value. This may be accomplished so that, to a fair approximation, the absolute voltage change at the plate of tube 68 is proportional to the percentage voltage change at the grid 67. Thus the output voltage change is independent of signal level.

Now as the signal rises and falls the voltage at the plate of the vacuum tube 68 rises and falls. This rise or fall of plate voltage causes a charging current to flow through a condenser 76 and a resistor 78 to ground. A voltage is therefore, produced across the resistor 78 that is proportional to the rate of rise or fall.

If the signal and plate voltage of the vacuum tube 68 are rising, the voltage across the resistor 78 is positive. This causes no significant action. The loop antenna 10 is presumably rotating towards a position of maximum response.

After the loop 10 rotates beyond the point of maximum response, the signal begins to fall. The percentage rate of fall is proportional to the product of the rotative speed of loop antenna 10 and the tangent of its angle of departure from the point of maximum response.

This produces a negative voltage across the resistor 78. Assuming a constant loop rotative speed, the magnitude of this voltage is proportional to the tangent of the angular departure of loop 10 from maximum and, as we have seen, is nearly independent of the strength of the received signal.

This negative voltage is conducted through a resistor 90 to the grid 91 of a vacuum tube 96 causing its plate current to decrease, and its plate voltage, because of the decreased drop in a resistor 98 to increase.

After these voltages attain a certain value, subject to a slight delay in time because of a pair of condensers 92 and 100, the first trigger tubes consisting of a pair of vacuum tubes 102 and 104 are tripped in the following manner:

The vacuum tube 104 is normally operated with its plate current saturated. Its grid is at cathode potential and is only prevented from going substantially positive, by virtue of the limiting action of a pair of resistors 112 and 75

114. This current flowing through a resistor 106 biases the cathode of the vacuum tube 102 to a point considerably more positive than its grid, thus holding its plate current extinguished.

5 The plate of the vacuum tube 96 is coupled through a resistor 117 to the grid of the vacuum tube 102. Therefore, the rising potential at the plate of the vacuum tube 96 is carried to the grid of the vacuum tube 102 so that it soon enters 10 the conducting region at which point the plate current flowing through a resistor 108 causes the plate potential of the vacuum tube 102 to fall. As this action continues, this plate voltage soon falls to the point where the potential distribution across the resistors 112 and 114 is such as 15 to bring the grid potential of the vacuum tube 104 below its cathode potential. This causes a decrease in its plate current and hence a decrease in drop across the resistor 106.

20 A resistor 110 is made very much smaller than the resistor 108. Also because of the amplification of the vacuum tube 102 its grid changes potential less than that of the vacuum tube 104. Both of these effects cause the decreasing current of the vacuum tube 104 to over-ride the increasing current of the vacuum tube 102. Therefore, the net drop across the resistor 106 decreases and the cathode of the vacuum tube 102 becomes less positive. But the grid potential has been made more positive by the tripping signal so it is evident that the effects just described effectively increase the exciting voltage once the tripping potential has been reached.

25 In fact, the currents promptly surge so that the plate current of the vacuum tubes 102 and 104 reach saturation and extinction respectively. This surge is accentuated by the charging current through the condenser 100 so that the action is practically instantaneous regardless of the 30 rate at which the tripping voltage rises. This new condition of equilibrium continues as long as the tripping voltage is maintained. If the rate of change of the signal should decrease or cease this tripping voltage will fall and at a 35 definite release value surges will take place in a reversed manner and the circuit will restore to normal.

40 This releasing voltage is somewhat lower in magnitude than the tripping voltage. This is an advantage as it prevents momentary surges from causing multiple trips.

45 The instant the vacuum tubes 102 and 104 are tripped and prior to their release, a second trigger circuit is actuated which controls the direction of rotation of the loop antenna 10.

50 This trigger circuit consists of a pair of vacuum tubes 116 and 118 in the respective plate circuits of which are a pair of fields 120 and 122 for an actuating motor 124 for antenna 10. The armature of the motor 124 is continuously supplied with power so that the motor 124 runs continuously in one direction or the other depending upon which of the two field windings 120 or 122 are receiving current.

55 60 65 This second trigger circuit, like the first is unstable, unless the plate current of one of the two tubes 116 or 118 is extinguished. In this condition the circuit is stable until, being tripped by the first trigger circuit, the current in the conducting vacuum tube 116 or 118 is extinguished and the current rises to normal in the vacuum tube 116 or 118 that was extinguished. This switches the fields 120 and 122 of the rotating motor 124 causing it and the loop 10 to reverse 70 direction of rotation.

The grid of vacuum tube 116 is held at a definite potential by the voltage divider consisting of a pair of resistors 130 and 132. An identical voltage divider consisting of a pair of resistors 134 and 136 determines the grid potential of the vacuum tube 118. Note that in each case the voltage dividers extend from a ground to the plate of the opposite vacuum tube 115 or 118.

The plate voltage of the extinguished vacuum tube 116 or 118 is much higher than that of the one carrying normal plate current. This is because of the absence of voltage drop across the motor field 120 or 122 through which plate currents are drawn. Therefore, each tube 116 and 118 maintains a suitable grid potential for the opposite tube. Each grid potential is positive but that of the extinguished tube is substantially less so. The cathodes are, therefore, positively biased by a common cathode resistor 138 so that the relative grid potential of the extinguished vacuum tube is substantially negative and well below the extinction point. The relative grid bias of the conducting vacuum tube is also negative but only by a moderate amount so that its plate current is responsive to any change introduced at the grid.

The grids of the vacuum tubes 116 and 118 are connected through a pair of condensers 126 and 128 to the plate of the vacuum tube 102. This plate voltage drops suddenly when the first trigger circuit is tripped. This negative pulse is impressed on the grids of the vacuum tubes 116 and 118. This, directly, causes no significant change in the plate current of the extinguished vacuum tube. The plate current of the other vacuum tube is however, suddenly dropped towards extinction. This causes a reduction of current through the resistor 138 and hence a reduction in cathode potential. Likewise, the fall in plate current of the conducting vacuum tube causes a rise in its plate voltage. This rise, reduced in magnitude, is transmitted to the grid of the extinguished vacuum tube where it overcomes the negative pulse potential as received from the first trigger circuit. Plate current now begins to flow producing a plate voltage change that transmitted to the other grid, accentuates the change.

The conducting condition of the two vacuum tubes 116 and 118 is now reversed. Likewise there has been an interchange of current between the motor fields 120 and 122. This causes the motor 124 to stop and reverse. This motor 124 causes the loop 10 to rotate through suitable reduction gears such as 140 and 142. Consequently the rotation of loop 10 also reverses direction and now moves towards the point of maximum response with a resulting rise in signal strength.

This rise acting through the rate of change circuits causes the first trigger circuit to release, if it has not already done so. This produces a positive pulse through the condensers 126 and 128 to the second trigger circuit. This produces no significant action and the pulse promptly decays.

The loop antenna 10 continues to rotate, crosses the maximum to the region of falling response. When it reaches the point where the rate of fall is of the designed magnitude, the trip circuits again function and again reverse the direction of rotation of loop 10.

Thus it is evident that the loop will continue to oscillate to equal angular displacements each side of the point of maximum response. The actual bearing is of course its average position.

It is desirable that the relatively large loop

oscillations be reduced in magnitude as indicated by an azimuth indicator 146. To accomplish this a hunting integrator may be interposed in shafting 147 between the loop 10 and the azimuth indicator 146.

Such an integrator forms the subject matter of a pending application for U. S. Letters Patent, Serial No. 707,730, filed November 4, 1946, now Patent No. 2,447,171. This is symbolically shown as indicated by the numeral 144.

In the above description several important features have been omitted as not being absolutely essential to the operation of the direction finder. These features do contribute materially to its operation in a really practical and satisfactory manner.

Such are a pair of rectifiers indicated by the numerals 80 and 82. The conducting direction is in each case as indicated by the arrow. These 20 could be thermionic diodes but are more conveniently of the germanium crystal type.

By means of a voltage divider consisting of resistors 84, 86 and 88, the rectifier 82 is biased negatively and the rectifier 80 is biased positively 25 with respect to the resistor 78. This places a positive bias on the grid of the vacuum tube 96 so a resistor 94 is incorporated producing a positive cathode potential slightly greater than that of the grid.

As previously explained a definite negative voltage is required across the resistor 78 to trip the circuit. The bleeder current and the resistor 88 should be so proportioned that the drop across the resistor 88 is slightly in excess of this voltage 35 value.

The rectifier 82 has little effect on voltages up to the trip value as the back resistance is very high. Voltages appreciably above the trip value however, cause conduction in the rectifier 82 so 40 that these excess voltages are substantially absorbed or clipped.

In this manner a noise or static surge is limited and if of short duration will not trip the circuit due to the delay imposed by charging the condenser 92 through the resistor 90 and the condenser 100 through its associated resistors 98 and 100 together with plate resistance of tubes 96 and 104. Suitable time constants for these circuits are approximately .05 second. The rectifier 50 80 is positively biased in a similar manner and serves to clip positive voltage surges in the same way. The resistor 86 is of the same magnitude as or slightly less than the resistor 88.

It is desirable that all audio modulation and 55 other fluctuations be removed from the rectified carrier before transmittal to the rate of change circuits. Now static noise bursts may cause a rapid change in carrier strength. Such changes should be accommodated with little delay so that 60 they may be effectively clipped and delayed as previously explained.

If long time constant filters are used the effectiveness of the clipping is greatly reduced. For these reasons the resistor 88 and the condenser 65 40 should have a time constant of about .01 second. A resistor 150 and a condenser 148 should have a time constant about the same.

A resistor 154 and a condenser 152 which govern the screen voltage of the pentode 30, 70 should have a time constant of about .02 second. Now the screen contributes only about 20% of the current so the additional delay will not cause any great direct change in the current rise or fall. But the plate and screen currents are but little affected by the plate voltage and greatly affected 75

by the screen voltage. The effect is such as to resist change in current.

Therefore the effect of the relatively slow time constant filter on the screen is to provide a delay in the restraint imposed by its voltage change. This results in a somewhat higher initial change in total current which reaches its ultimate value without the excessive tapering off that is usually characteristic of resistance capacity filters.

It was previously explained how the vacuum tubes 30, 56 and 68 functioned so as to be independent of signal level variations. Now this is true only throughout the limited operational range of the tubes in question and would by no means accommodate the signal strength ratio encountered in practice, which may be many thousandfold.

The need for some sort of volume control is evident. A simple manual volume control would serve but its inconvenience would indicate the desirability of an automatic volume control.

Now the conventional volume control tends to prevent change in the rectified carrier, which is precisely the effect required in this direction finder. Such a volume control would require excessive time delay in the automatic volume control circuits and excessive trip circuit sensitivity. This is undesirable for several obvious reasons.

The automatic volume control employed, operates to reduce or increase the amplification to any desired degree or at any desired speed. Over a limited range it is however, almost completely ineffective. It is within this range that all of the action previously explained takes place.

Two rectifiers are employed acting between an automatic volume control buss 166 and the cathode of vacuum tube 30. A first rectifier 156 is conductive towards, and a second rectifier 158 is conductive away, from the cathode of vacuum tube 30.

At the initial no signal condition the cathode of vacuum tube 30 reaches a positive potential somewhat greater than that of the cathodes of the vacuum tubes being controlled. A bleeder current may be drawn from the plate supply source to the cathode bias point through a pair of resistors 50 and 51. These resistors should be so proportioned that, at their junction, the positive potential will equal the positive potential of the cathode of vacuum tube 30 at the no signal condition.

A resistor 161 should have about four times the resistance of a resistor 160. Now, as the signal increases, the cathode potential of vacuum tube 30 decreases in positive potential. The positive cathode potential of the rectifier 156 likewise decreases but the decrease will be one-fifth smaller in magnitude.

As the incoming signal continues to increase, the cathode potential of the rectifier 156 will eventually drop below that of the automatic volume control bus 166. When this takes place, the conductivity of the rectifier 156 is such, that the AVC bus 166 will then have its positive potential reduced. This rapidly decreases the amplification of the receiver until a balance is reached.

If the signal subsequently decreases, the cathode potentials of vacuum tube 30 and the rectifier 156 rise. No immediate change occurs in potential of the AVC bus 166, as the rectifier 156 is now non-conductive. If the change continues the cathode potential of the vacuum tube 30 soon exceeds the potential of the AVC bus 166. At this point the rectifier 158 becomes conductive and the potential of the AVC bus

166 rises with the potential of the cathode of the vacuum tube 30. This rapidly increases the amplification of the vacuum tube receiver until a balance is reached.

5 This will permit a change in signal strength of any desired magnitude without automatic volume control action. If the resistors 160 and 161 are proportioned in the ratio of 1 to 4 a 20% drop in signal strength is required to start AVC action. This should be adequate to accommodate the direction finding functions.

10 Amplification changes may be made at any desired speed by controlling the charging rate of a condenser 164. If desired these speeds may 15 differ for increases and decreases in amplification.

15 The condenser 164 is charged through a resistor 162 for increases in amplification and discharged through the parallel combination of 20 the resistors 160 and 161 for decreases in amplification.

25 It is evident that, throughout all of the volume control action just described, and for all operating conditions, the grids of all vacuum tubes being controlled are at positive potential from ground.

30 It is necessary, however, that the receiver tubes being controlled operate at all times with their grids negative with respect to their cathodes. It is, therefore, necessary to bias these cathodes positively to the same degree as the initial automatic volume control bias.

35 This may be conveniently done by connecting all the cathode returns of the receiver tubes 35 being controlled to a wire 168 which is connected to the same positive bias source that was used for the cathode of the vacuum tube 68.

40 An additional desirable precaution would be to limit the maximum positive excursion, of the automatic volume control bus, to the cathode potential of the receiver tubes. This may be done by providing a diode rectifier within one of the receiver tubes. This diode is connected between its cathode and the automatic volume control bus. This diode is non-conductive when 45 the bus is less positive than the cathode.

50 Satisfactory loop rotative speeds have been found to be between 30° to 60° per second. Tripping may be readily accomplished at 30° or more from points of maximum response.

55 The foregoing description has described how automatic direction finding may be accomplished using only a single antenna.

Due to the well known directional characteristics of a loop antenna two bearings 180° apart are always found. Under the conditions just described this 180° ambiguity is likewise experienced in this direction finder.

60 This uncertainty may be resolved by employing a sense antenna. In this case, as in the case of previously used direction finders, the phase of the signal received by the loop antenna signal is compared to that received by the sense antenna. Now the phase of the sense antenna signal is constant while that of the loop antenna shifts 180° as it rotates across the point of no response.

65 For several reasons it was found undesirable to receive the sense signal continuously. The sense signal is only applied momentarily following each tripping action.

The non-directional sense antenna 12 is connected to the grid of a vacuum tube 170. The grid is biased to ground through a pair of resistors 200 and 190. The resistor 190 is effectively

by-passed by a condenser 188 so that the effective termination consists of the resistor 200. This resistance 200 must be large compared to the reactance of the antenna and associated wiring, at the lowest frequency in the operating range. This is in order to maintain proper phase relations. One-half megohm is a suitable value for this resistance.

Suitable supply voltages are established for the plate, screen and cathode by means of resistors 178, 180, 182 and 184. These resistors are of such value that the positive cathode bias will nearly extinguish the plate current. A pair of condensers 172 and 174 effectively by-pass these resistors at radio frequencies.

The signal output from the vacuum tube 170 is transmitted through a transformer 176 to the input of the receiver in parallel with the loop antenna 10.

This transformer 176 should have a very close coupling between its windings. The secondary inductance should be several times the inductance of the loop antenna 10 so as not to unduly affect the transmission from the latter. The primary, connected to the plate of the vacuum tube 170, will have a very much lower inductance. This inductance should be just high enough to transmit sense signals of desired strength. Any transmission in excess of this is undesirable. The magnitude of this signal need not exceed 20% of the maximum signal of loop antenna 10.

It is evident that normally no sense signal is transmitted as the vacuum tube 170 is normally extinguished. Following each tripping action a pulse of short duration is transmitted in the following manner:

The cathodes of the vacuum tubes 102 and 104 are connected through a condenser 198 to the pulse shaping network consisting of the condenser 188, the resistor 190 and a resistor 192 and a pair of rectifiers 194 and 196. These rectifiers 194 and 196 may be of the germanium crystal type and their directions of conductivity are as indicated by the arrow.

When tripping action occurs a negative pulse is transmitted from the cathodes of the vacuum tubes 102 and 104 through the condenser 198 and is promptly absorbed by the rectifier 196. No significant action takes place in the circuits of the sense antenna 10. The loop rotating motor 124 slows down and then reverses. Shortly before or after this motor reversal the trigger circuit releases.

This sends a positive pulse through the condenser 198, rectifier 194 and the resistor 192 to the condenser 188 which is shunted by the high resistance 190. This charges the condenser 188 positively and through the resistor 200 places a positive voltage on the grid of the vacuum tube 170 thus rendering it conductive and permitting a sense signal to be transmitted to the receiver and associated direction finding circuits.

The sense signal must not be injected into the receiver 22 abruptly. If this is done the limiter and time delay circuits would prevent its transmission to the tripping circuit.

For this reason, the current charging condenser 188 is limited by the resistor 192 in series with the rectifier 194. A time constant greater than that of the resistor 90 and the condenser 92 is then obtained.

During this charging period the amplification of the vacuum tube 170 is continuously increased, causing a continuous increase in amplitude of the injected sense signal. The amplitude and

rate of this injected sense signal must be such as to be capable of actuating the tripping circuits. After the condenser 188 receives its maximum charge, it begins its discharge through the resistor 190 only the rectifier 194 being non-conducting for currents in this direction. The discharge resistor 190 is made much larger than the charging resistor so that the rate of change of the falling sense antenna signal will be too small to actuate the tripping circuits.

Now this momentary injection of sense signal may act in either of two ways depending upon which of the two ambiguous bearings the loop antenna is responding.

In the first way, the injected sense signal will be in phase with the loop antenna signal and a rise in combined signal will result. This causes no significant action. In this case the loop antenna 10 is oscillating about the proper bearing.

In the second way, the injected sense signal will be out of phase with the loop antenna signal. This indicates that the loop antenna 10 is oscillating about the wrong bearing. In this case a fall in the combined signal will result due to their difference in phase. This causes the tripping circuits to be reactivated and the loop rotation, after but a momentary hesitation, continues towards the point of minimum response.

The first trigger circuit is held tripped by the continuously falling signal and usually releases only after the point of minimum response is crossed. In such a case no further significant action will take place until the loop antenna 10 rotates beyond the opposite point of maximum response and again enters a region of falling signal response. Subsequent tripping and sensing actions will then continue about the proper point of maximum response.

A somewhat different action may result if the automatic volume control action is different. In this case after the retripping due to the sense pulse the trigger circuit is initially held in the tripped position as before. However, the continuously falling signal must shortly cause the automatic volume control to begin functioning. If the automatic volume control functions rapidly enough, it may increase the amplification almost as rapidly as the signal falls. In such a case the trigger circuit will release which in itself will cause no significant action. However, as rotation continues towards the point of minimum response, the rate of signal change rapidly increases and may again exceed the speed of action of the automatic volume control so that another tripping action will ensue. In such a case the sense cycle is repeated and, after but a momentary hesitation, loop rotation is continued as before. It is thus evident that in either case proper sense is assured.

When severe precipitation static exists, excessive noise is picked up by the sense antenna 12 that will only affect slightly a shielded loop antenna. Under this condition the sense antenna circuit may be disabled. This will still give continuous automatic direction finding but with 180° ambiguity. This may be accomplished by operation of a switch 186. This grounds the sense antenna 12 and adds a resistor 202 in the cathode bias circuit of the vacuum tube 170. The resistor 202 should be large enough to hold the vacuum tube 170 completely extinguished during sense pulses.

All plate voltages may be secured from a power source 62 which may be a battery, dynamotor or any other convenient source.

The filaments of all vacuum tubes may secure power from the source 64 which will usually be a storage battery but need not be restricted to such. The wiring of the filaments is not illustrated on the drawing as such methods are well known.

The several positive biases previously mentioned may be secured from the source 64 but are not restricted to such a source as they could be obtained from the source 62 or some other source without in any way affecting the operation.

Many obvious variations in the circuit described are possible without affecting its principles of operation. Among these are the following.

Any of the rectifiers may be thermionic diodes or other suitable types. The rectifier 32 may be separated from the vacuum tube 30.

Multigrid tubes may replace triodes and vice versa.

Selsyn motors may be used in place of indicator 146 for remote indication of azimuth. Deviation compensation may be associated with azimuth indication.

The loop rotating motor 124 may be controlled by a relay. Saturable core reactors controlling an alternating current motor could also be used.

Having thus described the invention, what is claimed as new and desired to be secured by Letters Patent is:

1. In a radio direction finder of the kind described, structure adapted to receive and transmit radio signals, said structure being rotatable, whereby the amplitude of the transmitted signals changes as the structure rotates; automatic means for rotating said structure in either of two directions; an electric circuit connected with said structure for receiving signals therefrom; circuit elements operably connected with said electric circuit and responsive to the rate of change in amplitude in said signals for controlling said automatic means; and filtering means for rendering said elements less responsive to bursts of static received by said electric circuit.

2. In a radio direction finder of the kind described, structure adapted to receive and transmit radio signals, said structure being rotatable, whereby the amplitude of the transmitted signals changes as the structure rotates; automatic means for rotating said structure in either of two directions; an electric circuit connected with said structure for receiving signals therefrom; circuit elements operably connected with said electric circuit and responsive to the rate of change in amplitude in said signals for controlling said automatic means; and filter means interposed between said electric circuit and said circuit elements for delaying the application of changes in signal amplitude to said elements, whereby to reduce effects of bursts of static received by said electric circuit upon said elements.

3. In a radio direction finder of the kind described, structure adapted to receive and transmit radio signals, said structure being rotatable, whereby the amplitude of the transmitted signals changes as the structure rotates; automatic means for rotating said structure in either of two directions; an electric circuit connected with said structure for receiving signals therefrom; circuit elements for controlling said automatic means; means interposed between said electric circuit and said circuit elements for applying voltage to said elements only during changes in amplitude of said signals; and filter elements for delaying the application of said voltage to said elements.

4. In a radio direction finder of the kind de-

scribed, structure adapted to receive and transmit radio signals, said structure being rotatable, whereby the amplitude of the transmitted signals changes as the structure rotates; automatic

5 means for rotating said structure in either of two directions; an electric circuit connected with said structure for receiving signals therefrom; circuit elements for controlling said automatic means; means interposed between said electric circuit 10 and said circuit elements for applying voltage to said elements only during changes in amplitude of said signals; filter elements for delaying the application of said voltage to said elements; and means for limiting the said voltage applied to 15 said filter elements.

5. In a radio direction finder of the kind de-

scribed, structure adapted to receive and transmit radio signals, said structure being rotatable, whereby the amplitude of the transmitted signals

20 changes as the structure rotates; automatic means for rotating said structure in either of two directions; an electric circuit connected with said structure for receiving signals therefrom; circuit elements operably connected with said

25 electric circuit and responsive to the rate of change in amplitude in said signals for controlling said automatic means; and an automatic volume control interposed in said electric circuit and having parts operable to control amplification of said signals outside a predetermined limited range.

6. In a radio direction finder of the kind de-

scribed, structure adapted to receive and transmit radio signals, said structure being rotatable, whereby the amplitude of the transmitted signals changes as the structure rotates; automatic

30 means for rotating said structure in either of two directions, an electric circuit connected with said structure for receiving signals therefrom; circuit elements operably connected with said elec-

35 tric circuit and responsive to the rate of change in amplitude in said signals for controlling said automatic means; and an automatic volume control interposed in said electric circuit and having

40 parts operable to control amplification of said signals outside a predetermined limited range, said parts including a pair of rectifiers arranged to decrease and increase the amplification by said

45 electric circuit as the magnitude of said signals increase and decrease respectively.

7. A radio direction finder comprising rotatable structure adapted to receive and transmit radio signals; means connected to said structure for receiving signals therefrom, said means

55 including an amplifier tube and means to rectify the carrier frequency voltage of said signals; automatic means for rotating said structure in either of two directions to produce a change in amplitude of the incoming signals; circuit ele-

60 ments responsive to the rate of change in amplitude and actuated by the rectified carrier frequency voltage for reversing the direction of travel of said structure rotating means as the amplitude of the received signals changes; and

65 an automatic volume control having a pair of rectifiers arranged for conduction toward and away from said amplifier tube for decreasing and increasing the amplitude of said carrier voltage as the magnitude of the signals increases and decreases respectively.

8. In a radio direction finder of the kind de-

incoming signals; a sense antenna; an electric circuit connected with said structure and said antenna for receiving signals therefrom; circuit elements operably connected with said electric circuit and responsive to the rate of change in amplitude of said signals for rendering said automatic apparatus operable to normally oscillate said structure about either of two possible positions where the magnitude of the signal received by said structure is at maximum; and means for applying the signals emanating from said sense antenna to the electric circuit to control said circuit elements only while said structure tends to oscillate about one of said positions.

9. A radio direction finder of the character described comprising rotatable structure adapted to receive and transmit radio signals; automatic apparatus having reversible parts for rotating said structure in either of two directions to produce a change in amplitude of the incoming signals; an electric circuit connected with said structure for receiving signals therefrom; circuit elements operably connected with said electric circuit and responsive to the rate of change in amplitude of said signals for periodically reversing said automatic apparatus; and means for rendering said automatic apparatus operable to oscillate the structure about only one of two possible positions where the magnitude of the signal received by said structure is at maximum.

10. A radio direction finder of the kind described comprising rotatable structure adapted to receive and transmit radio signals; automatic apparatus having reversible parts for rotating said structure in either of two directions to produce a change in amplitude of the incoming signals; a non-directional sense antenna; an electric circuit connected with said structure and said antenna for receiving signals therefrom; circuit elements operably connected with said electric circuit and responsive to the rate of change in amplitude of said signals for periodically reversing said automatic apparatus; and means including said sense antenna for rendering said automatic apparatus operable to oscillate the structure about only one of two possible positions where the magnitude of the signal received by said structure is at maximum, said means having parts for directing signals from said sense antenna to said electric circuit only momentarily at each reversal of said automatic apparatus.

11. A radio direction finder of the kind described comprising a rotatable structure adapted to receive and transmit radio signals; automatic apparatus having reversible parts for rotating said structure in either of two directions to pro-

duce a change in amplitude of the incoming signals; a non-directional sense antenna; an electric circuit connected with said structure and said antenna for receiving signals therefrom; 5 circuit elements operably connected with said electric circuit and responsive to the rate of change in amplitude of said signals for periodically reversing said automatic apparatus; and means including said sense antenna for rendering said automatic apparatus operable to oscillate the structure about only one of two possible positions where the magnitude of the signal received by said structure is at maximum, said means having parts for directing signals from said sense antenna to said electric circuit only momentarily at each reversal of said automatic apparatus, said parts rendering said momentary signal operable to control said circuit elements only upon the tendency of said automatic means to oscillate the structure about the other of said two possible positions.

12. A radio direction finder of the kind described comprising rotatable structure adapted to receive and transmit radio signals; automatic 25 apparatus having reversible parts for rotating said structure in either of two directions to produce a change in amplitude of the incoming signals; a non-directional sense antenna; an electric circuit connected with said structure and 30 said antenna for receiving signals therefrom; circuit elements operably connected with said electric circuit and responsive to the rate of change in amplitude of said signals for periodically reversing said automatic apparatus; and 35 means including said sense antenna for rendering said automatic apparatus operable to oscillate the structure about only one of two possible positions where the magnitude of the signal received by said structure is at maximum, said 40 means having parts operable to control said circuit elements only when the signals received by said sense antenna are incorrectly phased with the signals received by said structure.

JOSEPH G. SPEER.
